UNITED STATES PATENT OFFICE

113,784

DESIGN FOR A TEXTILE FABRIC

Louis Kaufman, New York, N. Y.

Application January 7, 1939, Serial No. 82,215

Term of patent 3½ years

To all whom it may concern:

Be it known that I, Louis Kaufman, citizen of the United States, residing at 555 Eighth Avenue, New York city, in the county of New York and State of New York, have invented a new, original, and ornamental Design for Textile Fabric, of which the following is a specification, reference being had to the accompanying drawing, forming part thereof.

Fig. 1 is a perspective view of the textile fabric showing my design,

Fig. 2 is a plan view of the textile fabrics, and Fig. 3 is a side view thereof.

The design consists of a series of cartridge pleats separated by fagoting, as shown.

I claim:

The ornamental design for a textile fabric, substantially as shown and described.

LOUIS KAUFMAN.
